UNITED STATES PATENT OFFICE

2,197,826

ENVELOPE FASTENER MACHINE

Abraham Novick, Flushing, N. Y., assignor to
 F. L. Smithe Machine Co., Inc., New York,
 N. Y., a corporation of New York

Application May 13, 1937, Serial No. 142,393

29 Claims. (Cl. 1-3)

The present invention relates to a novel method and apparatus for applying fastening devices and similar attachments to envelopes and the like, and is to be regarded as an improvement upon the 5 type of fastener-applying machine, and the procedure, disclosed in my Letters Patent No. 1,771,732.

In that patent, the envelopes are fed sidewise from a suitable source of supply in a direction 10 parallel to the cover flaps, and upon reaching the station at which the fastening or other devices are to be applied, relative movement is caused between each envelope and an insertable anvil, in a direction perpendicular to the direction of feeding, and after the fastening means has been attached, the sidewise feeding movement of the envelope is resumed.

In contradistinction to the above procedure, it is the primary object of the present invention to 20 provide for supplying the envelopes successively in a lengthwise direction from a supply in which the envelopes are supported in face to face relation; most desirably with their closed bottom edges resting on the support, which avoids a disadvantage encountered when the envelopes are 25 supported on one of their longer edges, with the closed bottom edges at one lateral margin of the stack and the thinner open cover flaps at the opposite lateral face of the stack.

It is difficult to secure an even arrangement 30 of the envelopes when the thick bottom edges are at a lateral face of the stack, and the envelopes often do not start upon their travel through the machine in proper alignment with the feeding devices. When each envelope follows a direction 35 parallel with its longitudinal major axis; in pursuance of the present invention, each fastener can be attached during a simple dwell of the envelope in its normal path of movement; and another object of the invention is to make provision for reciprocatory movements of an anvil device into 40 and out of the open, trailing end of the envelope, while the envelope is held stationary in said normal path. At each fastener-applying operation 45 the envelope will be arrested in proper register with a fastener-applying station having a vertical plunger, the operating axis of which is normal to the path of travel of the envelope and perpendicular to a broadside portion of its body; this 50 axis being preferably disposed in a fixed vertical line intersecting the longitudinal, major axis of the envelope, which coincides, as above indicated, with the medial straight line of advancement.

This movement of the anvil into the envelope, 55 while the latter retains its position in its normal

path of advancement, is much better than another mode of operation disclosed in said patent, which involves pushing the envelope out of its path toward the anvil, for the reason, in the first place, that the envelope is flimsy to handle, and 5 may buckle undesirably, increasing the difficulty of manipulation. Under the novel provision of the present invention, the eventual buckling to effect the opening of the walls of the envelope to receive the anvil is of brief duration and is 10 accomplished under control by a suitable mechanism.

So also the reciprocating movements of the anvil, toward and away from the fastener-applying station, are accomplished according to a co-operative feature of the present invention, by a mechanism which is effective eventually, by a swift movement, to retract the anvil for the short distance necessary to position it where the next envelope in the feed line will slide readily over it, 20 the envelope just completed being simultaneously freed to resume its advance, thus reducing to a minimum the duration of the dwell for each operation and consequently making it possible to run the machine at optimum speed. 25

It is a cognate object of the invention to accomplish the operation of applying a patch to the flap, and to perforate the flap and patch simultaneously, concurrently with the application of the fastener, during the above-mentioned dwell. 30

As an object of the invention ancillary to the feed of the envelopes lengthwise instead of sidewise, is the provision made at the supply point for improved separation of each envelope by an improved sucker-and-rotor combination transfer 35 device; a notable feature of this improved action residing in effecting the separation without linear advance of the separated envelope until initiation of the transfer proper.

Another object served by the straight-line advancement without deviation is to avoid hooking action at any time, between the anvil and the envelope, or undesired engagement of associated mechanisms by a curled flap of an envelope, which may occur when the envelopes are moved 45 sidewise; nor will the patch material hook upon the flap, nor upon other parts of the envelope, when the latter is moved lengthwise.

A further object of the invention is to permit feeding movement of the patch material and of 50 the fasteners, only when an envelope is in course of proper approach to the patch-applying station, for which purpose the invention provides a novel control device, set positively by a sensing or feeling mechanism actuated only when an en- 55

velope is coming up to its proper position, the control device being biased by suitable means to bar movement of the patch-feeding mechanism whenever an envelope fails to arrive properly.

5 Complemental means are provided to bar operation of the fastener-feed mechanism at such times.

Another object is to provide supporting means and actuating means for the patch-applying mechanism, and for the other mechanisms, so disposed aside from the path of the envelopes as not to obstruct their straight-line advancement at any time.

Another object is to provide for accurate registry of the anvil, as well as of the envelope, with the axis of the fastener-applying tool, by means of a suitable stop means for each.

A further object is to so coordinate the foregoing instrumentalities that all of the operations 20 will be effected by exclusively mechanical means, automatically; also so that the several mechanisms other than the fastener-applying means will be adjustable relatively to the fixed axis of reciprocation of the fastener-applying tool, thus 25 making it possible to adjust the entire machine readily, so far as necessary, for operating upon different sizes of envelopes.

Another object is to provide a novel method of applying a fastener or like attachment to an 30 envelope; said method, broadly stated, comprising the step of advancing the envelope past an anvil; stopping the envelope; inserting the anvil by advancing it in the same direction; applying an attachment to the envelope; then withdrawing the anvil and simultaneously resuming the advancing movement of the envelope.

Other and ancillary features and objects of the invention will appear as the description of the particular physical embodiment selected to illustrate the invention progresses.

In the accompanying drawings, like characters of reference have been applied to corresponding parts throughout the several views which make up the drawings, in which:

45 Fig. 1 is a view in vertical sectional elevation of a machine in the construction of which the present invention is embodied the section being taken on the line 1—1 of Fig. 3;

Fig. 2 is a view in plan of an envelope to which 50 has been attached a fastener device, and a flap reinforcement perforated to cooperate with the fastener device;

Fig. 3; is a view in horizontal section on the line 3—3 of Fig. 1;

55 Fig. 4 is a fragmentary view, and upon a larger scale, of the left hand end of Fig. 1;

Fig. 5 is a fragmentary detail view in vertical section on the line 5—5 of Fig. 6;

Fig. 6 is a fragmentary detail view in plan 60 upon a larger scale, showing certain of the parts illustrated in Fig. 3;

Fig. 7 is a view in side elevation taken on a larger scale, and illustrating also certain parts not shown in Fig. 1;

65 Fig. 8 is a fragmentary view in plan of a portion of Fig. 7;

Fig. 9 is a fragmentary detail view in plan of part of the feeler mechanism and the conveyor belts;

Fig. 14 is a fragmentary detail view in vertical section taken on the line 14—14 of Fig. 3;

Fig. 15 is a fragmentary detail view, similar to 5 Fig. 14, of the same parts, shown in a different operative position;

Fig. 16 is a fragmentary detail view in vertical section taken on the line 16—16 of Fig. 15;

Fig. 17 is a view from a similar viewpoint, but 10 showing the anvil and envelope in a different operative position;

Fig. 18 is a fragmentary detail view in vertical section taken on the line 18—18 of Fig. 3;

Fig. 19 is a view similar to Fig. 18 showing 15 some of the parts of Fig. 18 in a different operative position;

Fig. 20 is a fragmentary detail view in section on the line 20—20 of Fig. 21 and on an enlarged scale, of the patch-applying mechanism, embodying the parts illustrated in Figs. 5, 11, etc., and illustrating particularly the mechanism to support the severed patch en route to the envelope;

Fig. 21 is a fragmentary detail sectional plan view of the parts shown in Fig. 20, taken on the 25 line 21—21 of Fig. 21;

Fig. 22 is a fragmentary detail view in vertical section, taken on the line 22—22 of Fig. 21;

Fig. 23 is a fragmentary detail view in vertical section, similar to Fig. 22, but showing the parts 30 in their operated position;

Fig. 24 is a fragmentary detail view of the mechanism for feeding fasteners to the fastener-applying station, with an added means for incapacitating the same at times;

Fig. 25 is a fragmentary detail view in horizontal section taken on the line 25—25 of Fig. 24;

In a now-preferred embodiment of the invention selected for illustration and description, and referring first to Fig. 1 of the drawings, a supply 40 of envelopes is illustrated at S, in the form of a stack of such envelopes as that illustrated in plan in Fig. 2, the envelope components of the stack being supported on plates 11 engaged with the folded, closed bottom edge 12 of each envelope, the envelopes extending upward lengthwise so that their open ends 13 stand at the top of the stack, and preferably with the flap opened, as shown in Fig. 2, but extending upwardly, although the envelopes may be stacked with the 50 flaps closed, and means may be provided to open the flaps prior to feeding, as set forth in a co-pending application Serial No. 152,245.

Adjacent to the bottom-supporting plates or members 11 for the stack is provided a finger 14 55 carried by an adjustable support 14x and engaged with the lowermost margin of the foremost envelope in the stack, which is intended to be the first envelope to be fed from the said supply stack.

In pursuance of the invention, by this disposition of the envelope components with their four-ply closed bottom parts in close juxtaposition to each other, a more even arrangement of the stack is possible than where the envelopes are disposed upon a support engaged with either of their side edges, such as 15.

When disposed as illustrated, provision is made, in pursuance of one object of the invention, for imparting additional support to the foremost envelope, as by means of an upright plate 16, mounted on a bracket 17 extending from the frame member 18, the lower edge 19 of the member 16 being disposed at a suitable dis- 70 75

tance from the finger 14, for a purpose now to be described.

Each envelope of the stack S as it arrives at the foremost position, as for example the envelope E shown in Fig. 1, is separated at its lower margin E' from the stack and drawn forward to the position at which E' is illustrated in Fig. 1.

This may be accomplished by any suitable separator device, and in the instance illustrated, this separating operation is performed by a sucker device S' the nozzle N of which can be oscillated by movement of a bail 20 around the axis of a pivot 21 journalled in a bracket 18x extending forward from the frame part 18.

The lower edge 19 of the plate 16 is disposed in substantial alignment with the axis 21 of rotation of the sucker bail 20, so that when the sucker nozzle N pulls the margin E' of a blank away from the stack, the portion of the envelope so withdrawn describes an arcuate path around the axis 21, with the result that during this separating operation there is substantially no linear advance of the envelope, such advance awaiting initiation of the transfer movement proper of the envelope lengthwise toward a means for advancing the envelope in a straight path through the machine.

Such transfer movement may be accomplished by any suitable means, and in the instance illustrated, provision is made therefor in the form of a pair of rotary transfer members, as R', R'', each of which is provided with a peripheral gripper G illustrated best in Figs. 12 and 13.

These rotors and the grippers may be of substantially conventional form, and upon reference to Figs. 12 and 13 it will be seen that each gripper comprises a segmental pinion 22, rotatably mounted on a stud 23 and engaged with a segmental rack 24, the latter being secured as at 25 (see Fig. 13), upon a shaft 26, mounted in bearings 27 in the rotor discs R' and R''. Upon the shaft 26 is also mounted a crank 28 provided with an anti-friction roller 29. The rotors R', R'' are mounted on, and rotate with, a shaft 30, actuated by a gear 36, and the roller or follower 29 travels on a fixed cam 31, this cam being mounted upon a boss 32 forming part of the frame member 18, and which serves as a bearing for the adjacent end of the shaft 30.

Upon the latter is pinned, as at 34, a cam C7 to which reference will be made later. An arm 26X, pinned upon shaft 30, as at 30X, affords a bearing for the shaft 26 adjacent to the crank 28.

Upon reference to Fig. 13, it will be noted that the shaft 26 serves to operate both of the segmental racks 24, so that the pair of grippers G will act in unison and exert an even grip upon the leading edge of each envelope.

The shaft 26 has secured thereto a crank arm 31 provided with a spring 37X by which it is biased to maintain the follower roller 29 into engagement with the cam 31.

Turning to Fig. 10, it will be seen that the gear 36 upon shaft 30 is in mesh with a gear 39 upon a driven counter-shaft 3, which is actuated, through suitable helical gearing 2, by the main driving shaft 1, and the rotation of rotors R' and R'' in the direction of the arrow upon the gear 36 (see Fig. 1), i. e., counter clockwise, initiates the transfer movement of the envelopes, the grippers G pulling lengthwise upon the leading closed bottom edge 12 of the envelope whose forward margin E' has been already separated to the position shown in Fig. 1.

The above combination of sucker separating device and rotor transfer members may be constructed in accordance generally with known devices for the same purpose, it being understood, however, that the provision of the plate 16 around the lower edge 19 of which the envelope may be bent prior to the initiation of lengthwise displacement, as already described, constitutes a novel improvement over existing structures and is herein claimed as such.

Progressive withdrawal of the envelope then ensues, so that eventually the forward edge 12 thereof is introduced into the bite of the transfer devices, i. e., at the point T indicated in Fig. 1. This reference character designates a region of tangency between the rotors R', R'' and a pair of spaced-apart conveyor belts B' and B'', the belts being arranged in a run which extends from idler pulley 41 on a shaft 40 carried by brackets 4 bolted as at 5 upon the base B of the frame to pulley 42 driven by a bevel gear 44 engaged with a complementary bevel gear 45 upon the driving shaft 1 (see Fig. 3).

Along this belt conveyor, which extends in a straight line through the run of mechanism 25 by which the various operations are performed, is extended a guide, as G1, under which the envelopes pass and which depends from brackets 46 and 47 mounted at one side of the table or base plate B, this guide having a jog or bend J 30 (see Fig. 9) in order to clear machine elements with which it might otherwise interfere. Suitable well known springs or rollers not shown may cooperate with the belts B' and B'' to press 35 the envelopes thereagainst to assist in feeding the envelopes.

In the instance illustrated, the operations to be performed upon each envelope include the application thereto of at least two different attachments, viz., a fastener element and a patch element.

A suitable form of fastener element is illustrated at F' in Fig. 2 and conventional form of patch element is there illustrated at P'.

It is intended that the patch P' shall be adhered to the flap 10 of the envelope and that the flap and patch shall be provided with a perforation 9 which is so formed as to receive the tongues 8 of the fastener element F', in known fashion, the fastener and the patch being spaced 50 apart at distances from the fold line 7 suitable to insure cooperation of the perforated patch with the fastener F'.

For the purpose of performing such operations of attachment as are required to apply the reinforcement patch and the fastener, the drawings illustrate a patch-applying station designated generally A', and a fastener applying station A'. The last-named of these stations is preferably disposed at the main axis of the machine, 60 defined by a reciprocating plunger A which operates along an upright axis normal to the path of straight-line travel of the envelopes defined by the belt conveyors B', B'' it being understood that the plunger A, therefore, operates in a direction perpendicular to the broadside face of the envelope E. At this fastener-applying station is provided preferably a chute C through which may be delivered in series a suitable supply of fastener blanks F', from a hopper H (see Figs. 1 and 7) in known or suitable fashion.

In the instance illustrated, the chute C is carried in suitable fashion by a yoke 90 mounted upon a rock-shaft 91 (see Figs. 7, 8 and 11) supported by an extension 117a of a bracket 117.

The shaft 81 is provided with an arm 82 connected by a link 83 with a lever 84 fulcrumed at 85 on a fixed bracket 86. The lever 84 has a follower 87 engaged with a cam 88 on the drive shaft 1, a spring 89 acting to bias the follower 87 against the cam 88.

By the action of the spring 89 and the cam 88, the chute C is adapted to be swung toward and away from the axis of the plunger A, and 10 the plunger is provided with a set of prongs 51 (see Fig. 7), which serve to enter the apertures 6x in the lobes 6 of each fastener element F' (see Fig. 2) as each such fastener blank or element is presented beneath the plunger by the 15 nozzle N' of chute C.

Such engagement of the prongs 51 acts both to assure correct registry of the fastener element for the clinching operation, and also to assure proper withdrawal of the fastener blank from the 20 nozzle N' of the chute C when the chute is retracted from the position shown in Figs. 1 and 7, toward the right hand, as indicated by the arrow in Fig. 7.

The chute may desirably have a yielding gate, 25 as 52, acting to restrain yieldingly the exit of the fastener elements in succession from the nozzle of the chute. This is known practice and does not require further elaboration.

In pursuance of the presence invention, the 30 envelope is arranged in position to receive the fastener and such other attachments as it may be desired to apply thereto, and for this purpose the invention provides a stop means designated in Figs. 1, 3 and 7 generally by the reference character M. Such stop means may desirably be provided with upwardly extending fingers 53, 54, shown clearly in Figs. 18 and 19, and which are carried by a block 55, in which the shanks of the fingers may be adjusted laterally.

40 In the instance illustrated, the block 55 mounted upon a rail 67 carried by a plunger 56 which enters a cylinder 57 beside which is mounted a spring device 58 (see Fig. 7), tending to bias the block 55 and fingers 53 and 54 upwardly into the position shown in Fig. 18, where they project 45 into the path of the envelope E, as the latter is advanced along between the belts B', B''.

Accordingly, the stop mechanism is normally 50 biased to its operative upward position, and provision is made for retraction of the fingers 53, 54 at suitable intervals of time, to release the envelope held thereby at the proper time, and accordingly the permit resumption of the advancement of the blank E by the belts B', B''. For such 55 retraction, a lever 59 is shown (see Fig. 18) mounted pivotally as at 60 upon a bracket 61 carried by the base B, said lever having an arm 63 provided with a follower 64 which is biased against the periphery of a cam 65 mounted to rotate with 60 the shaft 1 as illustrated in Fig. 8 and Fig. 18.

As the cam turns, the roller 64 runs up on a shoulder 66 of the cam, and the lever 59 is depressed positively, carrying down with it the block 55 and fingers 53, 54 against the bias of the spring 58, thus releasing the envelope for resumption of its advancement as already indicated. Adjacent to the station at which the fingers 53, 54 thus arrest each envelope, is provided a pair of self-weighted rollers 71 (see Figs. 70 1 and 3), each carried by an arm 72 mounted pivotally, as at 73, upon a bracket 74 which is secured by a pin 75 to a rod 76 passing through an upright 77 carried by the frame base B.

The rollers 71 may be adjusted relatively to 75 the stop fingers 53, 54 and held in adjusted po-

sition by means of a thumb screw 78 in known fashion. The rollers 71 and arms 72 are thus adapted to act as hold-down members, in a manner well understood by those skilled in the art. They prevent any tendency of the forward end 5 of the envelope to curl up or jump upward during the performance of the various attachment operations thereupon, and prevent rebound of the envelopes from the stops 53 and 54. Suitable tables 79 are provided, to extend beneath the 10 belts B' and B'' for the purpose of supporting them and the envelope at the region where the rollers 71 rest thereupon.

It will be noted at this point that the block 55 can be adjusted along the rail 67 in order to 15 act properly upon envelopes of different length. Binding screws 68 serve to hold the yoke in adjusted position on the rail 67, as indicated in Fig. 1, and the rail is mounted directly on the plunger 56, as already mentioned. A supporting bracket 20 69 for the tables 79 serves as a guide for the rail 67 to prevent rotation thereof about the axis of the plunger 56.

As an outstanding feature of the present invention, it has already been indicated that the 25 envelopes are each held in arrested position in the straight path of advancement, without any deviation therefrom, in any direction during the entire series of attaching operations performed upon each envelope; and as a means to that end, 30 provision is made of an improved form of anvil device, adapted to be entered between the walls of the envelope, to cooperate with the fastener-applying mechanism, this entry being accomplished by advancing the anvil device in the same 35 direction as that in which the envelopes are individually advanced in their straight path throughout the run of mechanism of which the machine is made up.

The anvil device is designated generally by the 40 reference character V and is shown in full lines in Figs. 1 and 3, this being its retracted position. A clearance is provided at 80 between the anvil and the underlying structure, through which the belts B' and B'' advance each envelope in turn, 45 the body and flap of each envelope thus lying in a plane below that of the anvil, so that the anvil does not interfere in any way with advancement of the envelope in its straight line path of travel.

When the envelope has been arrested by the 50 stop fingers 53, 54, it is held there in readiness to receive the anvil at its trailing end, but before the anvil is advanced, provision is made for separating the body wall of the envelope at its open 55 end so that there will be no failure of the anvil to enter properly.

As suitable means for effecting this operation, use is made of an upwardly moving finger 82 (see Figs. 14-17 inclusive), carried by a plunger 83 which is normally biased upwardly by a spring 84 (see Fig. 7), mounted beside the plunger casting 85, and operating as does the spring 58 which actuates the plunger 56 for the stop fingers 53, 54.

Normally, however, the spring bias is counter- 65 vailed by the action of the arm 86 of a lever mounted pivotally at 87 upon a bracket 88 extending upwardly from the base B and this lever has an arm 86x with an anti-friction roller 89 engaged with the periphery of a cam C' mounted 70 on and secured to the shaft 1.

When a gap c of the cam is brought under the roller 89 the bias of spring 84 becomes effective to draw the plunger 83 and finger 82 upward into the position shown in Fig. 15, in which the finger 75

acts to press upwardly the lower wall *e* of the envelope, as shown clearly in Fig. 16, the effect of this buckling action upon the lower wall being to create a corresponding buckling action of the upper wall *e'* so that the forward end of the anvil *V* can gain ready access to the opening *e''* of the envelope in advance of the flap *10*.

This upward movement of the finger *82* is only momentary, and immediately upon entrance of the leading end of the anvil *V* between the envelope walls, the roller *89* again rides upon the larger radius of the cam *C''* and retracts the finger *82* to the position shown in Figs. 14 and 17, releasing the envelope walls, which then assume the position shown in Fig. 17, embracing closely the forward end of the anvil.

The anvil is now in the position shown in dash-dot lines in Fig. 3, to cooperate with the tool when clinching the fastener element *F'*, the latter being shown in its initial position in Fig. 17, but not yet described. Before describing the clinching, a description will be given of the means by which the anvil is advanced from the position of Fig. 16 to that of Fig. 17.

In pursuance of this important object of the invention, the means for operating the anvil are disposed largely aside from the path of direct travel of the envelopes through the machine, and for this purpose the anvil is shown as provided with a downwardly extending member *101* guided in a slot *101x* and to which is connected a rod *102* which is connected at its other end, as at *103*, pivotally with a pitman *104* (see Figs. 1, 3, 4 and 11). This pitman swings from a remote pivotal support *105* upon the frame member *18x*, and has at an intermediate point *106* a pivot on which is mounted a follower roll *107*, adapted to be engaged with the periphery of a cam *C3* which is mounted on the countershaft *3*. The roller *107* is biased normally toward the cam by a spring *108* shown at the bottom of Fig. 4. The spring-bias is limited by an abutment *109* in the path of the free end of lever *104*. This assures correct alignment of the anvil recesses *u* with the tool *Ax* (see Fig. 17).

As shown in Fig. 4, the roller *107* is engaged with that part of the cam *C3* which is of greatest radius, and during which engagement the anvil is held in its retracted position of Figs. 3 and 16. When the shoulder *C3* of the cam has passed the roller *107*, during clockwise rotation of the cam, the roller descends quickly along the slabbed-off portion *C4* of the cam, permitting the spring *108* to move the anvil forward with a quick thrust to the position shown in dot-and-dash lines in Fig. 3 and also shown in Fig. 17 already described.

It will be noted in Fig. 17 that the forward end of the anvil is provided with a series of cup shaped recesses designated respectively by the reference character *v*; these being adapted to aid in clinching the projections *f* which extend downwardly from the fastener *F'* and are to be bent over into clinching relation with the under side of the upper wall *e'* of the envelope, in usual fashion. This operation is effected by descent of the plunger *A* which carries a tool *Ax* adapted for the purpose. The blow of the plunger is absorbed by a stationary anvil *Vx*, Figs. 1 and 17.

It is not necessary to describe the clinching operation in detail as the same may be effected in known fashion and it will be sufficient for the purpose of the present description to describe principally the actuating means for the plunger *A*.

Upon reference to Figs. 7, 8 and 11, it will be

noted that a lever *110* is provided, actuated by a cam *C5* secured to shaft *1*, which cam is engaged with an antifriction roller *111* mounted at the free end of the lever *110*, the latter being pivoted on a shaft *112* and having an arm *113* with a forked leading end *114* pinned as at *115* to the portion *116* of the plunger *A*.

The plunger *A* works in vertical bearings provided in brackets *117* and *118* of a standard *119* extending upwardly from the base *B*.

Connected with the pivot *115* (see Fig. 7), is a cam device at *120* bearing an anti-friction roll *121* which serves as an auxiliary means for clearing the chute *C* from the path of plunger *A* in the event that there should be any failure in withdrawal of the chute *C* by its actuating mechanism *90*, etc., hereinbefore described. The roller *121* is adapted to be engaged with a shoulder cam *122* affixed to the chute *C* so that descent of the plunger *A* is always accompanied by retraction of the chute *C*, although reliance may be ordinarily placed upon the mechanism *90*, etc., for such retraction, in order to relieve the plunger *A* of this duty except as an emergency measure.

This standard serves also to support way *123* (see Fig. 7) guiding a plunger *123* at the bottom of which is a cross head *125* formed as at *124* with horizontal slideway in which is carried a head *127* which forms part of the patch applying mechanism now to be described.

The principal elements of this patch-applying mechanism are shown in plan in Fig. 6, and include a plunger *128* which may desirably be rhomboidal in cross-section, as shown, working in upright slideways *129* of complementary shape, this plunger having at a central position a bore *126* serving as a bearing for a narrower plunger *130*, adapted for use in perforating the patch *P'* (see Fig. 2) after its application to the flap of the envelope in the manner now to be described.

Referring to Fig. 5 and Fig. 20, it will be noted that the plunger *128* has a cutting member *196* at its leading edge, this cutter being adapted to sever a patch part *P'* from a supply of adhesive strip *S''* fed thereto by suitable mechanism, a preferred form of which is illustrated principally in Figs. 6 and 7.

The patch supply strip, designated *S''*, is fed from a supply roll *W* thereof (Fig. 1), and may be provided with dried gum, and in that event it is intended to be remoistened by passing it through a suitable apparatus for that purpose which may be general of known character in the respect that it includes a pair of rolls *131* and *132* (see Figs. 6 and 7), between which the strip *S''* passes to the patch applying station.

These rolls are positively driven by intermeshing gears *134*, *135* actuated by a shaft *136* connected with a suitable driving mechanism, a pawl *138* (see Figs. 7 and 24), mounted at *139* on a lever *140* which is adapted to oscillate about the shaft *136*, the pawl being biased by a spring *141* against the notched periphery of the member *142*.

The lever *140* is swung to and fro positively by a system of links and levers *143*, *144*, *145* and *146*, the last-mentioned of which has an antifriction follower roller *147* engaged with a cam *148* upon the shaft *30*, and the system of link levers and, assisted by the cam *148* and a spring *148a* connected to the lever *146*, and causes oscillation of the frame *140*, and forward feeding of the strip *S''* unless the lever system is restrained under the following conditions.

In pursuance of the invention, provision is made of means to prevent such feeding in the

absence of an envelope, and for this purpose a sensing mechanism is provided, including a feeler 151 (Figs. 7, 9 and 25) secured to a rock shaft 152 provided with an arm 153 connected pivotally with a link 154 having a slot 155 within which is engaged a pin 156 at the end of a strut 157 mounted pivotally at 158 upon a fixed plate 158a and which strut has an obstructing finger 159 disposed as shown in Figs. 7 and 24 in such position that it will be engaged with a shoulder 160 formed at the lower part of the lever 140, and will consequently prevent the operation of the lever 140 by its actuating mechanism.

The finger is shown in position to prevent the link and lever system 143, etc., from rotating the lever 140 clockwise, and this is due to the fact that the feeler 151 occupies its illustrated position below the level of the belts B' and B'', such position of the feeler being due to the fact that no envelope is coming past that position on its way to the patch applying station.

While an envelope is passing the position occupied by feeler 151, it leaves the latter, which, by rotation of shaft 152 and arm 153 serves to show the link 154 downward, and swing the end 159 of the strut 157 out of the path of the shoulder 160 of the lever 140. By means of the spring at 161 the connection between the link 154 and the member 157 acts to prevent damage to the mechanism if the finger 159 becomes jammed against the shoulder 160, in which event the spring 161 permits a certain oscillating movement of the link 154 without uncoupling. The spring 161x biases the feeler 151 downward, and a rail G3 supports the belt B' against the downward thrust of the feeler 151. This rail is of suitable length to permit adjustments of the feeler support 222 for use with different lengths of envelopes.

It will be readily understood from the above that this combination of follower, levers and link constitutes a mechanism which acts in the presence of an envelope on its way to the patch applying station to cause advancement of the strip S'' to such station, but in the event of failure of an envelope to approach the station properly, the operation of the strip-advancing mechanism is blocked to improper deposit of a gummed patch upon the underlying parts when there is no envelope present.

The roll 132 feeds the patch-supply strip S'' through an open trough 163, see Fig. 1, which has a curved portion 164 conforming with the curvature of the roll 132 and a straight portion 165 tangent to the roll 132 and extending through a block 166 (see Fig. 6 and Fig. 20) which has a fixed abutment 167 and an adjustable abutment 168 between which abutments the trough 165 is located and the shear blade 196 is clamped.

The block and the movable abutment, as shown best in Fig. 20, are transfixied by the plunger 128, and from the slide 127 extends downwardly a post 169 around which is coiled a spring 170 that bears at its lower end against a lug 195 on the rhomboidal plunger 128 so that the downward actuation thereof is of yielding character, and thus the movable shear 196 may be brought to rest and is prevented from damaging the underlying parts after it has severed the strip S'' over the stationary shear edge 196x, to cut off the patch P', and while the punch 130 moves on to punch the hole 9 into the patch and the flap 10 to which it is attached.

In Figs. 20 to 23 inclusive is shown a means

preferably employed with the patch-applying mechanism for the purpose of avoiding accidental displacement of the patch P' enroute to the envelope, after severance.

To this end, the rhomboidal plunger 128, is provided with a pair of leg-shaped members 185 (see Fig. 23), mounted in lateral, vertical grooves 186 symmetrically disposed at each side of the rhomboidal plunger, these members constituting latches with bevelled toes 187 projecting inward beneath the plane in which is fed the patch-supply strip S'', as shown clearly in Fig. 22, which illustrates the normal position of the parts associated therein.

Just as the trough-shaped guide member 165 has beveled inner side walls, as shown in cross-section at 165x in Fig. 5, so the toes 187 are bevelled and are thereby adapted to afford minimum edge contact with the gummed and moistened attaching surface of the strip and of each patch severed therefrom.

The latches 185 are biased normally to present their lower extremities 187 in "toed-in" disposition relatively to the edges of the patch P' (see Fig. 22), by the action of spring-pressed plungers 188 in sockets 189 of the rhomboidal plunger 128, screw-plugs 188x being provided to regulate the tension of the springs; and these plungers or dogs 188 are engaged with bevelled heads 190 of the latches, the latter deriving support from fulcrum 191 transfixing the upright bearing grooves 186. Thus the tendency of the latch parts 187 is to "toe-in" toward the patch part P' with a resistance which is designed to be overcome by the stronger force exerted by the spring 170 (see Fig. 20) against the lug 195 of the rhomboidal plunger 128 when the head 125 is caused to descend by the plunger 173 in the course of application of the patch, as already described.

From the foregoing description, it can be readily understood by those skilled in the art, that when the patch-applicator 128 descends, the shear member 196 moving with it, severs the leading end P' from the patch-supply-strip S'', and carries it down to the position illustrated in Fig. 23, during which transfer the patch is held between the toes 187 and the lower extremity 128x of the plunger 128.

The patch is thus ejected past the toes 187, which are spread by the plunger 128 to permit the lower gummed face of the patch to be pressed against and adhered to, the broadside face of the flap 10 of the envelope E; and thereafter the plunger 128 is retracted upwardly by means of the nut 197 screwed upon the threaded end 198 of the post 169, which causes the rhomboidal plunger to be retracted positively upon each upward movement of the cross-head 125. The latter is moved up and down by the plunger 173, which is actuated by a head 174 guided by a post 175 and actuated by a link 176 connected pivotally at 177 to the arm 178 of a lever 179 mounted loosely on the shaft 112, and having at its free end a follower 180, Figs. 7 and 8, biased toward a cam C6 on the shaft 1, by which the plunger 173 is depressed at suitably timed intervals.

Concurrently with the above operation, the inner plunger 130 is caused positively by the head 125 to perforate the flap 10 and overlying patch P', to form the usual orifice 9 (see Fig. 2), to which reference has already been made.

The anvil block B4, Fig. 20, is provided with a recess B5 to serve as a die in co-operation with 75

the perforator 130, and may desirably have a reinforcement plate B6, to present a readily maintained cutting mouth for such a die.

The structure above described assures the accomplishment, at each patch-applying operation, of the severance, transfer, attachment to the envelope flap, and perforation, of a clear-out, properly attached flap patch, free from disalignment from registry with the patch-applicator, and thus carries into effect this important object of the present invention.

In the event that no envelope comes up properly to the fastener-applying station, it is desirable that no fastener shall be fed thereto, in order to avoid waste and possible damage to the underlying parts, and provision is made by the present invention of means to accomplish this desired result by interposing a barrier in the way of the fastener-supply chute C so that the latter will be held positively against the bias of the spring 99 by which the chute is normally urged toward the feeding position illustrated in Fig. 7.

While such a barrier may be of another form, the intended purpose is illustratively served in the present instance by the provision of a strut 210, Figs. 24 and 25, mounted pivotally on the bracket 119, as at 211, and having a free end 212 notched to present downwardly a shoulder 213 which is adapted to trap a detent 214 on the chute C every time that the chute is swung away from the fastener-applying station, viz., during the operation of completing the clinching or attachment of each fastener to an envelope, in the manner hereinbefore described.

As the chute swings from the position shown in Fig. 7, to that shown in Fig. 24, the detent trails along the under surface of the strut 210 which is gravity biased against the detent, and serves to effect eventually the entrapment of the detent 214 by the shoulder 213.

In order to release the chute, it is necessary to raise the strut 210 positively, and for this purpose provision is made by the present invention to impart to the strut a lifting movement originating in the sensing means associated with the patch feeding mechanism, and which includes the mechanism actuated by the feeler 151 when the latter is raised by an envelope approaching the patch-applying station. This has been described already, and need not be again described, it being only necessary to recall the fact that when coupled by the feeler action, the arm 140 will be oscillated to and fro to advance the patch-strip feeding rolls 131-132.

Accordingly, by the added mechanism shown in Figs. 24 and 25, a connection is provided in the form of a rocking bar or lever 215 which extends across the abutment or fulcrum 216, reaching from the pitman 143 to an arm 217 depending from the strut 210, and which acts, when the rocking bar 215 is swung downward by the pitman 143, to push the arm 217 upward and thus tilt the strut 210 upward around its pivot 211, thereby raising the notched end 212 of the strut to clear the detent 214 and permit the chute C to be swung to feeding position, under the bias of the spring 99 (see Fig. 7).

Conversely, when the feeler 151 drops to its position shown in Fig. 24, and as long as no envelope comes along to raise the feeler, the strut 210 will occupy the position shown in Fig. 24 and will bar movement of the chute C to its feeding position. The tool A may still reciprocate in the axial line of the fastener-applying

action, but as no fasteners will be fed, there can be no damage to the underlying parts, and no waste of material.

Upon reference to Fig. 25, it will be seen clearly, that if the arm 217 which carries the patch-applying mechanism be adjusted laterally with the aid of bolts 218X, extending through slots 219 of the plate 220, the abutment 216 can be shifted freely under the rocker rod 215 without in any manner interfering with the latter or changing its mode of operation. The rod 215 may have a limit collar 215x, to prevent its escape from the connection with the upper apertured end of the pitman 143.

Fig. 25 illustrates clearly also the long bearing 221 which is provided for the rock-shaft 152 on which the feeler 151 is mounted.

The moistener unit is designated generally by the reference character M3, and it has a bracket 223, Fig. 6, fixed, as by a bolt 224, to the head 225 of the arm 218 and will therefore be moved therewith when the arm is adjusted laterally by the bolts 218x already described.

In the operation of the machine, a stack S of envelopes having been placed upon the support 11, and a supply roll W of patch strip stock provided with its support w, and properly threaded through the guide trough 163, between the feed rolls 131 and 132, the machine will be started.

At the initial stage of operation, the sucker 30 nozzle N will first be carried forward against the forward margin E' of the innermost envelope of the stack and then moved to the position of Figs. 1 and 4 by the cooperative action of the cam C7, follower c7, lever 181, rod 182, sucker lever 20 35 and sucker spring 183, and then the grippers G, as shown in Fig. 12, will be closed upon the edge 12 of envelope margin E' by the action of crank 28 as its follower 29 rides up on the shoulder 31x of cam 31. 40

The initiation of lengthwise feeding of the envelope, thus begun in an arcuate path, will be translated into advancement along the straight path defined by conveyor belts B' and B'' when the bottom edge of the envelope has been thrust 45 into the bite at T (see Fig. 1) of the belt-rotor assembly, and the envelope will be advanced through the clearance 80 between the belts and the anvil V until its edge 12 is engaged between the stop fingers 53 and 54, as shown in Fig. 18, 50 which have been raised to arresting position by the bias of spring 58, which raises plunger 56, rail 67, yoke 55 and the fingers. At this position, the envelope is held, as shown in Fig. 3, with its flap 10 open and extending beneath the 55 rhomboidal patch-applying plunger 128, and with its walls e, e' still unopened; the anvil V occupying the full-line position of Fig. 3, above the flap 10 and beneath the rhomboidal patch-applicator 128. 60

In order to clear the patch-applicator, and at the same time to align the anvil V and the plunger A at the fastener-applying station A', the bias of spring 108 (see Fig. 4) is now made effective by rotation of cam C3, clockwise, and the aforesaid spring draws the pitman 104 in a right-hand direction until it is stopped by the abutment 109, thus pushing in the same direction the link 102 which acts upon the shank V' of the anvil V (see Fig. 3) to move the anvil in 70 the same direction that the envelope has been advanced.

The anvil is secured to a slide 200 working in a yoke-shaped guide 201, and when the above advance of the anvil has been completed, it oc- 75

copies the position shown best in Fig. 17, entered between the walls *e*, *e'* of the envelope, which have been buckled open momentarily to receive the anvil, as shown in Figs. 15 and 16, by the finger 82, for which purpose the bias of spring 84 (see Figs. 7 and 14) has been made effective, by registry of cam notch *c* with follower 89 to permit the plunger 83 to rise momentarily; the said cam then acting to raise the lever arm 86, to depress the arm 86 and retract the finger 82, to permit the envelope walls to assume the position of Fig. 17, embracing the anvil *V*.

The chute *C* will now have been biased to its Fig. 7 position by the spring 99, to bring a fastener blank under the plunger tool *Ax*, and when the prongs 51 of the tool (see Fig. 7) have entered the openings 6x in the lobes 6 of the fastener blank (see Fig. 2) the chute is retracted positively and quickly by the action of cam 96 upon follower 94, link 93, lever 92, shaft 91, and arm 90. The tool now completes its clinching stroke, under the depressing action of the yoke 114 and lever 110, actuated by the cam *C*5 on follower 111, and sets the fastener, after which the follower 111 drops off the shoulder *c*6, and the spring 202 acts to raise the tool *Ax*.

At or about the same time, while the envelope *E* is still held in its arrested position of Fig. 3, and after the anvil *V* has been advanced to the dash-dot line position there shown, the patch-strip *S*'' will have been advanced by the moistener roll and feed roll couple 131—132 through the trough 165 (see Fig. 6), to the position shown in Fig. 5, ready to have its projecting end severed by the descent 35 of the shear 196 over the stationary shear 176. For this purpose, and to press the patch upon the flap 10, the rhomboidal plunger 128 is depressed by the action of the head 125 against spring 170, and the inner plunger 130 is also depressed to 40 perforate the patch and flap (see Fig. 2). This depression of the head 125 is accomplished by the plunger 173, link 176 and lever 178, the latter being depressed by the elevation of arm 179 through the action of cam *C*6 on follower 180. 45 After the patch has been applied and perforated the spring 203 acts to raise the head 125, thus clearing the way for retraction of the anvil, preparatory to repetition of the above cycle of operations, which may be repeated indefinitely 50 until complete expenditure of the supply of envelopes.

If, at any time, no envelope comes up properly to the sensing position occupied by feeler 151, the latter will occupy the low position shown in Fig. 55 24, depressing the strut 159 into position to be engaged with the shoulder 160 of lever 157 and the arm 140 can not be swung clockwise, thus incapacitating the pawl 138 and the rocking rod 215. At such times therefore, the shaft 136 will 60 not turn the feed rolls to advance the patch-strip nor will the strut 210 be raised, and the chute *C* will accordingly not be swung to feed fasteners.

I have described what I believe to be the best 65 embodiments of my invention. I do not wish, however, to be confined to the embodiments shown, but what I desire to cover by Letters Patent is set forth in the appended claims.

I claim:

1. The novel method of applying a fastener or like attachment to an envelope; said method comprising the step of advancing the envelope past an anvil with its closed bottom edge leading and its cover-flap open and trailing; stopping the envelope; inserting the anvil by advancing it in the direction in which the envelope is advanced;

applying an attachment to the envelope; then relatively withdrawing the anvil and the envelope lengthwise of the envelope path.

2. The novel method of applying a fastener or like attachment to an envelope; said method comprising the step of advancing the envelope past an anvil with its closed bottom edge leading and its cover-flap open and trailing; opening the envelope walls to receive the anvil; inserting the anvil therebetween by advancing it in the direction in which the envelope is advanced; applying an attachment to the envelope; then relatively withdrawing the anvil and the envelope lengthwise of the envelope path.

3. The novel method of applying a fastener or like attachment to an envelope; said method comprising the step of advancing an envelope past an anvil, with its open end and cover-flap trailing; stopping the envelope; applying a patch to the flap of the envelope; inserting the anvil in said open end by movement of said anvil in the same direction; applying a fastener to the body of the envelope; then relatively withdrawing the anvil and the envelope lengthwise of the envelope path.

4. In an envelope fastening machine, means for advancing an envelope in a straight path, means for holding said envelope in arrested position in said path, means for opening said envelope, and means for advancing an anvil into said opened envelope, in a direction running lengthwise of the envelope path.

5. In an envelope fastening machine, means for advancing an envelope in a straight path, means for holding said envelope in arrested position in said path, means for opening said envelope, and means for advancing an anvil into said opened envelope, in a direction running lengthwise of the envelope path, and means for retracting said anvil and the envelope lengthwise of the envelope path.

6. In an envelope fastening machine, means for advancing an envelope in a straight path, means for holding said envelope in arrested position in said path, means for opening said envelope, and means for advancing an anvil into said opened envelope, in the direction of the advancement of said envelope, means for applying an attachment to said envelope, and means for retracting said anvil and the envelope lengthwise of the envelope path.

7. In a machine for applying fasteners and similar attachments to envelopes and the like: the combination of means to feed a supply of envelopes successively in the direction of their lengths; means to advance said envelopes lengthwise along an exclusively straight, substantially unobstructed path; an attachment-applying station aligned with said path; means to stop each of said envelopes individually for a suitable dwell at said station; an anvil device adapted to be inserted into the open end of each envelope in succession, said anvil being reciprocable in a path substantially coinciding with the path of said envelopes, into and out of alignment with the attachment applying station; and actuating means adapted to effect said reciprocation of the anvil device.

8. In a machine for applying fasteners and similar attachments to envelopes and the like: the combination of means to feed a supply of envelopes successively in the direction of their lengths; means to advance said envelopes lengthwise along a straight, substantially unobstructed path; an attachment-applying station aligned with said path; means to stop each of said envelopes individually for a suitable dwell at said station; an anvil device adapted to be inserted into the open end of each envelope in succession, said anvil being reciprocable in a path substantially coinciding with the path of said envelopes, into and out of alignment with the attachment applying station; and actuating means adapted to effect said reciprocation of the anvil device.

velopes individually for a suitable dwell at said station; an anvil device adapted to be inserted into the open end of each envelope in succession, said anvil being reciprocable in a path substantially coinciding with the path of said envelopes, into and out of alignment with the attachment applying station; and actuating means adapted to effect said reciprocation of the anvil device, and means controlling the operation of said stop-means and acting at intervals to withdraw said stop from the path of each envelope, after each attachment operation, to permit the envelope to resume its advancing movement.

9. In a machine for applying fasteners and similar attachments to envelopes and the like: the combination of means to feed a supply of envelopes successively in the direction of their lengths; means to advance said envelopes lengthwise along a straight substantially unobstructed path; an attachment-applying station aligned with said path; means to stop each of said envelopes individually for a suitable dwell at said station; an anvil device adapted to be inserted into the open end of each envelope in succession, said anvil being reciprocable in a path substantially coinciding with the path of said envelopes, into and out of alignment with the attachment applying station; and actuating means adapted to effect said reciprocation of the anvil device, and means controlling the operation of said stop-means and acting at intervals to withdraw said stop from the path of each envelope, after each attachment operation, to permit the envelope to resume its advancing movement, said resumption becoming effective simultaneously with retrograde movement of said anvil.

10. In a machine for applying fasteners and like attachments to envelopes; means to supply envelopes successively in the direction of their lengths; means to advance said envelopes lengthwise along an exclusively straight, substantially unobstructed path; and applying station aligned with said path and having a reciprocating attachment-applying means operating along a predetermined axis disposed in a direction normal to said path and perpendicular to a broadside portion of the envelope; actuating means for said attachment-applying means; means to stop said envelopes individually at said station with a predetermined portion in alignment with said axis of the operating means; an anvil device adapted to be inserted between the body walls of said envelope, and reciprocable in a path substantially coinciding with that of the envelope, into and out of alignment with said axis of operation; an actuating means adapted to effect said reciprocation of said anvil device; and means controlling the operation of said stop-means and acting at intervals to withdraw said stop from the path of each envelope, after each attachment operation, to permit the envelope to resume its advancing movement, said resumption becoming effective simultaneously with retrograde movement of said anvil device.

65 means to feed a supply of envelopes successively 11. In a machine for applying fasteners and similar attachments to envelopes and the like; in the direction of their lengths, from a supply stack in which said envelopes are disposed with their closed bottom edges resting on a suitable support, means to advance said envelopes along an exclusively straight, substantially unobstructed path; an applying station aligned with said path; means to stop each of said envelopes individually for a suitable dwell at said station; an anvil de-

vice adapted to be inserted into the open end of each envelope in succession, and reciprocable in a path substantially coinciding with the path of said envelopes, into and out of alignment with said attachment-applying station; and a supporting means and an actuating means for said anvil device disposed predominately aside from said path, and adapted to effect said reciprocation of said anvil device.

12. In a machine for applying fasteners and like attachments to envelopes; means to feed a supply of envelopes successively in the direction of their lengths; means to advance said envelopes endwise individually along a straight, substantially unobstructed path; and a station aligned with said path, having patch-applying mechanism and fastener-attaching mechanism disposed in suitable positions relatively to each other to apply a reinforcement patch to the cover flap of each envelope, and to perforate said flap and patch, also having mechanism to rivet a fastener to the rear wall of the envelope, correctly spaced from said perforation to co-act therewith in fastening said cover flap when said flap shall have been folded into closed position.

13. In a machine for applying fasteners and like attachments to envelopes; means to feed a supply of envelopes successively in the direction of their lengths; means to advance said envelopes endwise individually along a straight, substantially unobstructed path; and a station aligned with said path, having patch-applying mechanism and fastener-attaching mechanism disposed in suitable positions relatively to each other to apply a reinforcement patch to the cover flap of each envelope, and to perforate said flap and patch; said station also having mechanism to rivet a fastener to the rear wall of the envelope, correctly spaced from said perforation to co-act therewith in fastening said cover flap when said flap shall have been folded into closed position; a stopping device to arrest each envelope in proper position at said station for the performance thereon of said patch and fastener applying operations; an anvil adapted to be inserted into the open end of the envelope to cooperate with said fastener-applying mechanism; and means for actuating said instrumentalities in coordinated timing, thereby to complete said operations by exclusively mechanical means.

14. A machine having the features claimed in claim 4, in which is provided a supply support, and means to remove said envelopes from the support and to transfer them, individualized in horizontal arrangement, to said means for their advancement along said straight path.

15. A machine having the features claimed in claim 4, in which is provided a supply support upon which the envelopes are arranged, and means to remove said envelopes from the support and to transfer them, individualized in horizontal arrangement, to said means for their advancement along said straight path, said supply support including a ledge to be engaged with a narrow margin of each successively lowermost bottom edge of an envelope as the supply is expended, the support also including a remote supporting bar arranged parallel with said ledge and serving to support and restrain the intermediate body portion of each envelope in course of removal; and a separator device adapted to be engaged successively with each lowermost envelope at the region near said ledge, said separator device being adapted to oscillate around an axis substantially coincident with the axis of said

- supporting bar, whereby, when the separator device is engaged with an envelope margin and pulls it away from the ledge and stack, the portion of the envelope thus carried away describes an arcuate path around said bar, and is free substantially from linear bodily displacement of the envelope until initiation of the transfer movement proper.
16. A machine having the features claimed in claim 4, in which is provided a supply support upon which the envelopes are arranged, and means to separate said envelopes from the supply and to transfer them, individualized in horizontal arrangement, to said means for their advancement along said straight path, said stack support including a ledge to be engaged with a narrow margin of each successively lowermost bottom edge of an envelope as the supply is expended, the support also including a remote supporting bar arranged parallel with said ledge and serving to support and restrain the intermediate body portion of each envelope in course of removal; and a sucker device adapted to be engaged successively with each lowermost envelope at the region near said edge, said sucker device being adapted to oscillate around an axis substantially coincident with the axis of said supporting bar, whereby, when the sucker device is engaged with an envelope margin and pulls it away from the ledge and stack, the portion of the envelope thus carried away describes an arcuate path around said bar, and is free substantially from linear bodily displacement of the envelope until initiation of the transfer movement proper.
17. A machine having the features claimed in claim 4, in which is provided a supply support upon which the envelopes are arranged, and means to separate said envelopes from the supply and to transfer them, individualized in horizontal arrangement, to said means for their advancement along said straight path, said transfer means including an oscillating sucker device and a rotary transfer member provided with peripheral gripping members adapted to grip the leading bottom edge of each envelope in turn, then to withdraw it from the sucker, the latter being de-energized for release of the envelope; a roll-couple adapted to receive in its bite the leading bottom edge of each envelope; and a belt conveyor adapted to receive the envelope successively from the last-named roll-couple, and to advance each along said straight path to be operated upon substantially as described.
18. A machine for applying fasteners and like attachments to envelopes: said machine comprising as elements means to advance envelopes individually in succession along a substantially straight path past a station at which a patch is to be applied to the flap of each envelope; reciprocating means at said station to press said patch against a flap and to perforate said flap and patch; means to feed a supply of adhesive strip patch stock between said reciprocating means and the path of said envelope; said patch-strip feeding means including a prime mover, a device for incapacitating said feeding means, means to bias said device normally to a position in which said feeding means is incapacitated, and a sensing device adapted to be set by an envelope, when properly coming up in its path for the patch-applying operation, to countervail said bias and rehabilitate the patch-applying mechanism; said patch-supply strip resting unfed when said bias incapacitates said feeding mech-
- anism, and so remaining inoperative as long as the envelope failure persists.
19. A machine of the class described having the features claimed in claim 4, in which the fastener-applying means operates along a fixed axis, and adjustable devices are provided whereby several mechanisms other than the fastener-applying means may be adjusted relatively to said fixed axis, thus making it possible to adjust the entire machine readily, so far as necessary, for operating upon different sizes of envelopes.
20. A machine of the class described, having the features claimed in claim 4, in which a self-weighted roll device is provided in position for engagement with the upper face of an envelope close to the region of said stop-means, tending to bias said envelope toward the means for advancing said envelopes in their path, said last-named means including a belt conveyor directly engaged with the under faces of the envelopes.
21. A machine of the class described for applying an attachment to an envelope: comprising means to advance a stock strip of attachment material to an attaching station; means to advance an envelope to said station at a substantial distance from said strip; means to sever a patch from the leading end of said strip and to press said patch toward the envelope; and means to clasp said patch in advance of said pressing means while in transit from the region of severance to that of application, said clasping means being adapted to yield resistsingly to pressure of the pressing means against said patch when contiguous with the envelope.
22. A machine having the features claimed in claim 21, in which means are provided to render adhesive a face of said strip, and a guide is provided for supporting said adhesive portion of the strip exclusively at its edges during transit to the severing station; and in which said clasping means are engaged exclusively with said edges of the patch in transit from the severing point to the point of application.
23. A machine having the features claimed in claim 21, in which the severing means and pressing means are embodied in a plunger and in which a plurality of latches are supported swingingly in lateral slots of said plunger, said latches having toes to clasp said patch lightly at its edges exclusively.
24. A machine having the features claimed in claim 21, in which the severing means and pressing means are embodied in a plunger and in which a plurality of latches are supported swingingly in lateral slots of said plunger, said latches having toes to clasp said patch lightly at its edges exclusively, and spring-actuated dogs to bias said latches to a toed-in position.
25. In a machine for applying fasteners to envelopes and the like; a fastener-applying station; means to advance an envelope to said station; means to feed a fastener to said station; periodically operating fastener setting means, and means to incapacitate said fastener-feeding means upon failure of an envelope to come up properly to said station, to cause the ensuing operation of the setting means to be an idle operation.
26. In a machine for applying fasteners to envelopes and the like; a fastener-applying station; means to advance an envelope to said station; means to feed a fastener to said station; and means to incapacitate said fastener-feeding means upon failure of an envelope to come up properly to said station, said station including a

reciprocating plunger, and said fastener-feeding means including a chute having a fastener outlet and adapted to be swung into position to present said fastener below said plunger; said incapacitating means including a bar, and means to bias said bar to a position in which it withstands swinging movement of the chute toward said feeding station.

27. A fastener-applying machine having the features claimed in claim 25; in which provision is made of means to rehabilitate said fastener-feeding means when an envelope comes up properly to said station.

28. In a machine for applying fasteners to the bodies of envelopes and reinforcing attachments to the closure flaps thereof, in combination, means for advancing the envelopes in a right-line path to a fastener and attachment applying station, means at said station for driving a fastener through a portion of the envelope body and for affixing an attachment to the closure flap thereof, said means being in alignment with one another in the direction of envelope feeding, an anvil insertable into the body of the envelope for cooperation with the fastener driving means, a carrier for the anvil, and means for reciprocating

the anvil carrier in the direction of envelope feeding, said anvil carrier being offset with relation to its path of movement to enable it to move clear of the path of the attachment affixing means when the anvil is in operative position. 5

29. A machine for applying fasteners and like attachments to envelopes: said machine comprising as elements means to advance envelopes individually in succession along a substantially straight path past a station at which a patch is 10 to be applied to the flap of each envelope; means to feed a supply of adhesive strip patch stock into juxtaposition with the path of said envelope; means to sever successive patches from said patch-strip, including a cross-head, slides in 15 which said cross-head is reciprocable in an upright path, a shear device mounted slidably on said cross-head, a perforating plunger also slidably mounted in said cross-head, a pressing means carried by said cross-head, means also 20 carried by the cross-head for embracing a severed patch and carrying it to the envelope; a prime mover, and means to connect said cross-head with said prime mover to permit said head to be reciprocated thereby. 25

ABRAHAM NOVICK.

CERTIFICATE OF CORRECTION.

Patent No. 2,197,826.

April 23, 1940.

ABRAHAM NOVICK.

It is hereby certified that error appears in the printed specification of the above numbered patent requiring correction as follows: Page 9, first column, line 65, strike out the words "means to feed a supply of envelopes successively" and insert the same before "in", line 68, claim 11; and that the said Letters Patent should be read with this correction therein that the same may conform to the record of the case in the Patent Office.

Signed and sealed this 18th day of June, A. D. 1940.

Henry Van Arsdale,
Acting Commissioner of Patents.
